UNITED STATES PATENT OFFICE.

EDWARD J. QUINN AND JOSEPH M. MALLEY, OF WORCESTER, MASSACHUSETTS,
ASSIGNORS TO MORGAN CONSTRUCTION COMPANY, OF WORCESTER, MASSACHUSETTS, A CORPORATION OF MASSACHUSETTS.

CONVEYER.

1,114,037.

Specification of Letters Patent. Patented Oct. 20, 1914.

Application filed February 17, 1913. Serial No. 748,815.

To all whom it may concern:

Be it known that we, EDWARD J. QUINN and JOSEPH M. MALLEY, citizens of the United States, residing at Worcester, in the county of Worcester and Commonwealth of Massachusetts, have invented a new and useful improvement in Conveyers, of which the following, together with the accompanying drawing, is a specification.

10 Our invention relates to conveyers and more particularly to a type of conveyer including a track and spaced prongs or teeth adapted to convey the articles.

Our improved conveyer is best adapted 15 for use in conveying articles which will lie flat upon the track of the conveyer and which have openings therein to receive the spaced prongs or teeth which move along the track to convey the articles. The most 20 common article of this class is a coil of wire.

An object of the invention is to construct a conveyer with a track having different portions thereof sloping at different angles, so that the articles will be moved by the conveying means past the intersection of the 25 different sections of the track without any danger of becoming disengaged from the conveying means.

Another object is to construct the track in such manner that the article, while passing from one section of the track to another, will always be supported firmly in position; that is, so that the article will not pass over such a ridge at this portion of the track as will 30 cause the article to lie at times in an unstable position. Because of the fact that the article is supported at each point of its passage in a fixed and predetermined position, the teeth or prongs which propel or convey the article, by being made to follow the fixed and predetermined path of the article, will more certainly engage the article throughout its 35 path.

Other objects and advantages will appear 40 from the following description taken in connection with the accompanying drawing, in which—

Figure 1 is a plan view of one form of our improved conveyer; Fig. 2 is a vertical sectional view upon the line 2—2 of Fig. 4; Fig. 3 is a vertical sectional view on the line 3—3 of Fig. 4; and Fig. 4 is an end view of the conveyer.

Like reference characters refer to similar parts in the different figures. 55

In the embodiment of the invention shown in the drawing, a conveyer track 1 is sufficiently wide to accommodate conveniently the articles to be conveyed along it and the side edges of the track are raised to form 60 walls 2 and 3 to assist in retaining the articles upon the track and in the path of the propelling mechanism. Along the longitudinal center of the track is a slot 4 in which runs a chain 5 carrying spaced prongs 65 or teeth 6 adapted to engage the articles and convey them along the track. The chain 5 is preferably of that type designed to run on sprocket wheels and, in the embodiment of the invention illustrated, three such sprocket 70 wheels 7, 8 and 9 are shown. It is obvious that if the chain were too long to be properly supported by this number of sprocket wheels, additional wheels might be provided at suitable intervals along the chain. To 75 drive the conveyer chain 5 any desired means may be used such as a gear wheel or a pulley and belt, the driving means being connected to one of the sprocket wheel shafts. 80

As has been stated, the track is in two portions, the slopes of the two portions being different, and one of the main features of the invention lies in the peculiar construction of the track at the intersection of its 85 two differently sloping portions.

The conveyer is adapted to convey articles to the upper end of an incline 10 and to start them down this incline. If the faces of the two sloping portions of the track were 90 continued until they met, it is clear that a sharp ridge would be formed at their intersection and that an article would be in unstable equilibrium while passing over this ridge. It is desired, too, that the prongs 6 95 engage each article at its forward portion while moving it along and, with such a ridge formed at the intersection of the two portions of the track, the forward portion of an article being conveyed past this ridge would continue moving in a direction parallel to that portion of the track along which it had moved prior to reaching the ridge. After the center of gravity of the article had passed beyond the ridge, the article 100 would, of course, tip forwardly to lie upon

the sloping portion of the track beyond the ridge. Before this occurred, however, the prong or tooth 6 engaging the article might very probably be withdrawn from the article so as to be disengaged therefrom, this being due to the fact that after passing the ridge the portion of the article engaged by the prong or tooth would rise farther and farther from the face of the track so as to allow the prong to pass thereunder unless, of course, the article tipped forwardly over the ridge in time to prevent this. To overcome this objection, the face of the track at the intersection of its two differently sloping portions is rounded off along the line 11 so that the two portions of the track merge gradually into each other. Each side 12 of the slot 4, however, is raised at this point so that the sides of the slot in the two portions of the track continue in their respective planes until they meet, except that the ridge at their intersection is rounded off slightly to provide a smoother path for the article. The sprocket wheel 8 is located at the intersection of the two portions of the track so as to guide the sprocket chain 5 and the teeth 6 along the path of the slot 4 rather than along the face of the track at this point.

When a ring-shaped article 13, such as a coil of wire, is to be conveyed, it is dropped onto the track over one of the prongs 6, as shown at the left in Figs. 1 and 2. The prong then moves the article along the track and, when the intersection of the differently sloping portions of the track is reached, the raised sides of the slot determine the path of the forward portion of the article and the engaging prong 6 is constrained to follow this same path by the sprocket wheel 8, there being no danger of the prong's becoming disengaged from the article. The sides of the article remain in contact with or, at least, close to the rounded off or depressed face of the track, the raised sides 12 of the slot extending upwardly into the opening in the article. The construction described provides a positive support for the article at three points at least, and at four points if the face of the track is not rounded off too much. When the engaging prong 6 reaches the sprocket wheel 9, it is, of course, withdrawn from the article, the article being deposited upon the incline 10 down which it slides or is pushed off by other articles following it. An article, too, that is not too narrow and that fits reasonably the space between the two walls 2 and 3 may be placed upon the track entirely ahead of one of the conveying teeth or prongs 6 so that the tooth or prong propelling it will engage it at its rearmost point. It will be seen that, in such case, if the entire face of the track at the point where the two differently sloping portions thereof meet were rounded off along the line 11, or if this portion of the track

were rounded off only slightly or not at all, the article, when it reached this point and tipped forwardly onto the second portion of the track, would tend to rise from the track at its rear portion so as to become disengaged from the conveying tooth or prong. By providing the raised central portion of the track, however, it is obvious that the engaging prong will follow the path of the engaged rear portion of the article, there being, therefore, no liability of disengagement.

While we have described in detail one embodiment of our invention, we do not wish to be limited thereto as it is obvious that certain changes may be made within the scope of the appended claims without departing from the spirit of the invention; but

What we claim as new and desire to secure by Letters Patent is:

1. A conveyer including a track, two adjacent portions of the track having different slopes, the sides of the track being depressed below the center thereof at the point where the said two portions meet.

2. A conveyer including a track, two adjacent portions of the track having different angles, the sides of the track being rounded off at the point where the said two portions meet, and the center of the track being raised above the sides thereof at said point.

3. A conveyer including a track, two adjacent portions of the track having different angles, the end of each portion nearest the other portion having its sides depressed below its general plane, but having its center lying in said plane.

4. A conveyer provided with an inclined track having a slot, with portions of the track upon each side of the slot raised above the face of the track, and means guided by said slot for moving articles over said track.

5. A conveyer including a track having raised sides, two adjacent portions of the track having different angles, with the face of the track depressed upon each side of the center where the two portions meet.

6. A conveyer including a track having a central longitudinal slot, and conveying means projecting from the slot and movable along the track, two adjacent portions of the track having different angles, the sides of the track being depressed below the center thereof at the point where the said two portions meet.

7. A conveyer including a track having a central longitudinal slot, conveying means projecting from the slot and movable along the track, a portion of the track having its center raised above the sides thereof, and means to cause said conveying means to move along said raised central portion.

8. A conveyer including a track having a central longitudinal slot, two adjacent portions of the track having different angles,

the center of the track being raised above the sides thereof at the point where the said two portions meet, a conveyer chain lying in said slot and provided with spaced teeth 5 projecting from the slot, supporting wheels for the conveyer chain, one of the supporting wheels being located at the raised central portion of the track to cause the conveyer

chain to move along said raised central portion, and means to drive the conveyer chain. 16

Dated this 12th day of February, 1913.
